C. W. DIBBLE ET AL

CARD REGISTERING MACHINE

Original Filed Sept. 27, 1920

UNITED STATES PATENT OFFICE.

CARROLL WALLACE DIBBLE AND MARION PHILLIPS, OF PORTLAND, OREGON, AS-SIGNORS OF ONE-FIFTH TO J. T. LOOFBOUROW, ONE-FIFTH TO J. G. MEEKS, AND ONE-FIFTH TO E. D. HOWE.

CARD REGISTERING MACHINE

Application filed September 27, 1920, Serial No. 413,055. Renewed March 12, 1925.

To all whom it may concern:

Be it known that we, CARROLL WALLACE DIBBLE and MARION PHILLIPS, citizens of the United States of America, and residents of city of Portland, Multnomah County, State of Oregon, have invented certain new and useful Improvements in Card Registering Machines, of which the following is a specification, reference being had to the accompanying drawing.

Our invention relates to the art of reproducing designs upon flat surfaces, such as cards or panels, for example, by aid of printing, stamping, stenciling, or any similar method of reproduction wherein substantially perfect alignment in the presentation of each card, for instance, in a run of cards, is required for each reproduction; and it has for its object the production of a machine for facilitating, expediting, and insuring accuracy of presentation of the card or the like upon which the design is intended to be displayed.

The form of embodiment of our invention herein illustrated is specially adapted for the reproduction of a design or picture upon a flat surface, as of a card, by the aid of a stencil. Accuracy of presentation of successive cards in a run of cards to the stencil is one of the important advantages obtained by the use of our machine. The method of producing a picture or design by the laying of color upon color through the employment of different portions of the design outlined or blocked out upon a single stencil plate or upon a succession of stencil plates, is one well known in the art of reproduction. It is to that method that our machine in the form of embodiment illustrated is especially applicable. In the method last referred to, substantial accuracy of registration between the lines of one stencil plate and another with reference to the card upon which the reproduction is to be effected, is necessary to secure the best artistic effect in the finished picture produced upon the card. It is one of the objects of our invention to provide a machine for securing that accuracy of registration, and for securing it with great economy of time and labor and consequent cost of reproduction. In this last connection, an important feature of our invention consists in substitut-

ing one means of alignment of the card, for instance, for another means of alignment whereby the alignment first obtained by the one means is secured and maintained by the other means with advantage in practicing certain methods of reproduction.

Other objects accomplished by our invention will appear to one skilled in the art from the following specification.

What constitutes our invention will be hereinafter specified in detail and succinctly set forth in the appended claims.

In the accompanying drawing a single figure in isometric perspective, of which portions are broken away to illustrate the relationship subsisting between its several parts, illustrates one of our machines in form of embodiment preferred for the purposes of this specification.

Referring to the numerals on the drawing, 1 indicates a flat surfaced bed-plate of any suitable and preferred shape and dimensions. It may be made of any suitable material such, for example, as wood, and stiffened, if desired in such case, by cross-pieces 2 secured to it from beneath, and which serve as supports for the bed-plate 1. The superficial area of the bed-plate is bounded by accurately, preferably rectangularly disposed edges 3, 4, 5 and 6. Parallel to the edge 3, for example, is a disappearing guide-member 7, and at right angles thereto is a disappearing guide-member 8. The members 7 and 8 are so mounted in the bed-plate as not to interfere in their operation one with another, being separated, for instance, by a clear space between their next adjacent ends as illustrated. The members 7 and 8 are designated by the term "disappearing" because of the function performed by them, namely that of presenting themselves as accurate guide-members in one phase of the operation of the machine, and of retreating, as occasion requires, substantially so as to coincide with the plane of the top of the bed-plate 1.

To the end last named, the guide-member 7 is preferably made of a piece of stiff sheet metal bent at right angles along a straight line 10 to form two integrally united plates 11 and 12 which are substantially L-shaped in cross section. Each of the plates 11 and 12 constitutes a true plane, and they meet

in the line 10 preferably in a true right angle. To one end of the plate 11 is hinged, as indicated at 15, a transverse plate 16, that is secured, as by countersunk screws 17 or other suitable means, to the bed-plate 1. The vertical plate 12 works within a straight kerf 18 provided for its accommodation in parallel relationship to the edge 3, for instance, and having a longitudinal extent sufficient to permit within it free movement of the plate 12 fastened at one end to the frame 1, as it is, by the hinge 15.

At right angles to the kerf 18 and parallel to the edge 5, for example, of the bed-plate 1, we provide a straight kerf 19 that corresponds in form and function to the kerf 18. The kerf 19 is provided for the accommodation of the vertical plate 20 upon the guide-member 8, that corresponds to the plate 12 on the guide-member 7. The guide-member 8 being substantially identical except, it may be, in longitudinal extent with the guide-member 7, and being united in like manner thereto to the bed-plate 1, needs no other description than that which applies to the guide-member 7.

The free ends of the guide-members 7 and 8 are adjacent to each other although preferably separated by an open space as illustrated, and, when elevated, as shown in the drawing, above the surface of the bed-plate 1, said guide-members present, in respect to their vertical plates 12 and 20, two planes that are relatively disposed to each other at a true right angle. Consequently, whenever a rectangular sheet, as of cardboard, for example, of sufficient dimensions to engage both of them at once, is inserted between them with its angularly disposed adjacent edges in true contact with each of them, the angle which unites those edges and the edges themselves will always effect a corresponding register with the sides 12 and 20 and the hypothetical angle of their junction. It is to effect this registration of a rectangular object laid between them that the members 7 and 8 are contrived.

The free ends of the members 7 and 8 are kept normally elevated by any suitable means, as, for example, by a bar spring 22 that is common to both the plates 12 and 20, and extends at its opposite ends into operative engagement with the lower edges of each of them, being medially secured to and supported by the bed-plate 1, as by staples 23 driven from below into the bottom of the bed-plate, as shown in the broken away portion of the drawing.

In respect to the above described card registering mechanism as it may be called, the machine already described constitutes an operative entity, which we regard as complete in itself, but with which we prefer to embody additional and cooperative

mechanism, as hereinafter described. To the end last named, we provide above the bed-plate 1 a cross-bar 25 that is made longitudinally adjustable in respect to the bed-plate 1, as by the aid of elongated slots 26 and 27 longitudinally disposed therein near its opposite ends. Adjustment of the bar 25 at right angles to its longitudinal axis is also provided for, as by longitudinal slots 29 and 30, formed, respectively, in opposite wing pieces 31 and 32 fastened to the edges 4 and 3, respectively, of the bed-plates 1, the tops of the wing pieces 31 and 32 being flush with the top of the bed-plate 1. Through bolts 33 and 34, respectively, provided each with its wing-nut 35, and passing through the slots 27 and 30, and 26 and 29, at their respective crossings, serve adjustably to secure the cross-bar 25 against the face of the bed-plate 1.

To the side of the cross-bar 25 that is toward the guide-members 7 and 8 is secured, as by suitable hinges 36 and 37, a rectangular frame 39, having a thickness transverse to its opening substantially equal to the thickness of the cross-bar 25 to which it is hinged.

In consequence of the relationship between the frame 39 and the cross-bar 25 as just described, it happens that whenever the frame 39 is depressed upon its hinges 36 and 37 so that the edges of the frame 39 and of the cross-bar 25 that are hinged together come into contact or nearly so, the bottom of the frame 39 will lie parallel and in close juxtaposition to the top of the bed-plate 1.

It is to secure the cooperation between the frame 39 and the bed-plate 1 last referred to that the guide-members 7 and 8 are contrived to functionate as disappearing guide-members. That is to say, they are adapted to efface themselves under pressure of the sides of the frame 39 sufficiently to permit the frame 39, notwithstanding their presence, to lie flat against the top of the bed-plate 1. The adjustability of the cross-bar 25 in respect to the bed-plate 1 is provided in order to accommodate frames of different superficial extent to the same cross-bar, and to render them, without respect to size within definite limits, presentable to the plates 11 of the guide-members 7 and 8, respectively. For this purpose the hinges 36 and 37 are preferably loose-joint butts whereof halves secured to the cross-bar 25 are made to accommodate complementary members provided upon a series of frames 39, of varying superficial extent if desired.

The relative movement between the frame 39 and the top of the bed-plate 1 may be controlled by other mechanism than the hinges 36 and 37 if a different movement than that obtained from a hinge connection be desired, but, for the purposes of this ap-

lication, we prefer to employ the hinge connection and in such case prefer, also, to provide a tensile spring 40 extending between a point of connection 41 with the frame 39 and a point of support 42 fixed as upon the end of an upright 43 upon the bed-plate 1. By this arrangement, provision is made for keeping the frame 39 normally elevated at an angle above the top of the bed-plate 1, as shown in the drawing.

The frame 39 illustrated is provided, in a plane substantially coincident with its under face, with a screen 45 which is made of permeable reticulated material, preferably a fabric such, for example, as bolting cloth of suitable and preferred weight and texture. When a permeable screen 45 is used, it is employed for the purpose of applying to it, by tracing or otherwise, the lines of a design in order that by stopping out certain portions of the screen from other portions thereof, as through the application of shellac, a stencil may be made. Through the permeable portions of a stencil so made 25 pigments dissolved in liquid (oil or water colors) may be forced against a surface as of a card laid upon the top of the bed-plate 1 and held in place thereon by a superposed frame 39 that carries the screen 45. The reproducing of designs by the aid of stencils is old and well-known in the art of reproduction to which our invention is applicable, and of which one skilled in that art will need no further description.

The frame 39, in respect to its mechanical function only of depressing the guide-members 7 and 8 and holding a sheet previously registered by said guide-members against the top of the bed-plate 1, may be used without the screen 45. Deprived of the screen 45, our machine may be employed for registering purposes only, and so utilized for reproduction methods such as stamping or printing in which the screen 45 is unnecessary, the sides of the frame 39 serving, in such case, as a guide to a stamping member, for example.

The operation of our device may be described briefly as follows.

The normal position of the several elements of the machine is shown in full lines in the drawing, the frame 39 being elevated so as to expose to an operator for convenient access the top of the bed-plate 1, and the free ends of the guide-frames 7 and 8 being elevated by their spring 22.

In this position an operator, standing upon the side of the machine indicated at 4, lays a rectangular card upon top of the bed-plate, and shoves it with a gentle force sufficient for the purpose into snug contact with the faces of the respective plates 12 and 20. Thus he depresses the frame 39 upon its hinges 36 and 37 until the bottom of the frame 39 meets the top of the bed-plate 1

or the card interposed therebetween. In its descent towards the bed-plate the frame 39 drives the free ends of the guide-members 7 and 8 against the top of the bed-plate when it engages the interposed card and holds it firmly in the registered position imparted to it by the guide-members 7 and 8 as above specified. After it is so engaged and held by the frame 39, the card is ready to be operated upon by application of a liquid pigment through the meshes of the screen 45, for example, or in any other method preferred.

It is here noted that the registering of the card is first effected by aid of the guide-members 7 and 8 which hold it in place, and that thereafter those members cease to function, and the frame 39 is substituted in their place with the additional function of securing the card in its previously registered position. Upon removal of the card, the operation above described may be repeated indefinitely.

What we claim is:

1. In a device of the class described, the combination with a rectangular bed-plate, of two disappearing guide members operatively disposed in parallel relationship, respectively, to two adjacent edges of the bed-plate, said guide members each provided with means engaging the top of the bed-plate for limiting their downward movement, said means being adapted to substantially coincide with the plane of the top of the bed-plate.

2. In a device of the kind described, the combination with a rectangular bed-plate, of two disappearing guide members operatively disposed in parallel relationship, respectively, to two adjacent edges of the bed-plate, each of said guide-members consisting of two plates angularly disposed towards each other, one plate being hinged at one end to the bed-plate and the other plate working in a vertical plane in a kerf provided for it in the bed-plate.

3. In a device of the kind described, the combination with a rectangular bed-plate, of two disappearing guide-members operatively disposed in parallel relationship, respectively, to two adjacent edges of the bed-plate, each of said guide-members consisting of two plates angularly disposed towards each other, one plate being hinged at one end to the bed-plate and the other plate working in a vertical plane in a kerf provided for it in the bed-plate, and means for keeping the free ends of the guide-members normally elevated above the top of the bed-plate.

4. The combination with a device of the class described, of a bed plate provided with a pair of guide members substantially L-shaped in cross section and pivotally secured to the adjacent edges of said bed plate,

a cross bar adjustably mounted on said bed plate, a frame hingedly connected to said cross bar and adapted to be brought into contact with the opposed sides of said guide members.

5. The combination with a device of the class described, of a bed plate provided with a pair of guide members substantially L-shaped in cross section and pivotally secured to the adjacent edges of said bed plate, a cross bar adjustably mounted on said bed plate, a frame hingedly connected to said cross bar and adapted to be brought into contact with the opposed sides of said guide members, and means secured to the inner faces of said guide bars for normally maintaining the said bars in the raised position.

6. The combination with a rectangular bed-plate, and a pair of disappearing guide-members substantially L-shaped in cross section and hinged at one end, respectively, to the top thereof and disposed, respectively, in parallel relationship to two adjacent sides of the bed-plate, and having their free ends normally elevated above the top of the bed-plate, of a rectangular frame, and means for hinging the said frame to the bed-plate.

7. The combination with a rectangular bed-plate, and a pair of disappearing guide-members substantially L-shaped in cross section and hinged at one end, respectively, to the top thereof and disposed, respectively, in parallel relationship to two adjacent sides of the bed-plate, and having their free ends normally elevated above the top of the bed-plate, of a rectangular frame, and adjustable means for hinging the said frame to the bed-plate for the purpose specified.

8. The combination with a rectangular bed-plate, and a pair of disappearing guide-members substantially L-shaped in cross section and hinged at one end, respectively, to the top thereof and disposed, respectively, in parallel relationship to two adjacent sides of the bed-plate, and having their free ends normally elevated above the top of the bed-plate, of a rectangular frame movable to and from the top of the bed-plate in fixed relationship thereto, and in cooperative relationship to the guide-members to actuate them for the purpose described, and means for normally keeping said frame separated from the top of the bed-plate.

9. The combination with a rectangular bed-plate and a pair of disappearing guide-members substantially L-shaped in cross section and hinged at one end, respectively, in parallel relationship to two adjacent sides of the bed-plate, and having their free ends normally elevated above the top of the bed-plate, of a rectangular frame, adjustable means for uniting said frame to the top of the bed-plate in hinged relationship thereto, and means in connection with said adjustable means for locating the frame in co-operative relationship to the guide members to actuate them for the purpose specified.

In testimony whereof, we have hereunto set our hands in the presence of two subscribing witnesses.
